UNITED STATES PATENT OFFICE.

LAURENCE S. LACHMAN AND EDWARD FULDA, OF NEW YORK, N. Y.

REEL.

Application filed July 12, 1920. Serial No. 395,453.

To all whom it may concern:

Be it known that we, LAURENCE S. LACHMAN and EDWARD FULDA, citizens of the United States, and residents of New York, 5 in the county of New York and State of New York, have invented certain new and useful Improvements in Reels, of which the following is a specification.

Our invention relates to the construction 10 of metal reels particularly adapted for motion picture films.

The object of the invention is to provide a strong reel, light in weight and one which will withstand the rough and hard usage 15 to which reels of this class are subjected.

The reel is constructed mainly of wire, preferably round in cross-section, so arranged and secured together that the reel, although of skeleton form will have great 20 rigidity.

A further object is to so secure the sleeve for the supporting spindle by which the reel is rotated that it will not become loose due to continued use of the reel.

25 A further object of the invention is to securely fasten the wires forming the side members of the reel to the hub in a simple manner.

The invention consists in the construction 30 of metal reel hereinafter more particularly described and then specified in the claims.

In the accompanying drawings, Fig. 1 is a side elevation of a metal reel constructed in accordance with this invention.

35 Fig. 2 is a transverse section taken on the line 2—2 Fig. 1.

Fig. 3 is an inside view of one of the side members for the reel.

Fig. 4 is an enlarged side elevation of 40 the hub barrel.

Fig. 5 is an end view of the same.

Figs. 6 and 7 are side elevation and end view respectively of the supporting spindle sleeve.

45 Referring to the drawings, the reel comprises two side members forming the side plates for holding the reel against edge-wise displacement in the reel. Each of these side members consists of a continuous peripheral ring 1 preferably of round wire and a plurality of wire elements 2 which join the peripheral ring to the hub in a manner to be presently described.

50 By forming the periphery of the reel of round wires liability to injury to the hand of the operator upon attempting to stop the

rotation of the reel by pressure of the hand is reduced to a minimum as compared with reels having sheet metal disks for the side members.

60 3 indicates hub plates or disks to which the wire elements 2 are secured. The wire elements 2 for each said member consist of wires suitably secured by welding to the wire rings and disposed at the point of attachment in a plane thereof so as to offer no lateral projection either inward towards the film or outward. They extend from the point of attachment or connection inwardly toward the center and are there suitably secured together as will be presently described, the two side members thus formed being joined to one another by a hub to complete the construction of the reel. They are preferably so proportioned and formed that they 65 make side contact with each other and with the inner surface of the peripheral ring 1. At these points of contact, indicated at 4, the parts are firmly secured together preferably 70 by the electric welding process.

75 The elements 2 have free ends 2' which contact with and intersect an annular ridge 5 formed on the hub plates 3. At such points of intersection the wires 2 and plate 3 are electrically welded together by means 80 of the ridge 5.

85 Preferably but not necessarily the free ends 2' of adjacent elements 2 are spread apart for the purpose of providing a sort of truss structure, thereby greatly increasing 90 the strength and also to provide, if desired, a repository for locking means to be presently described.

95 Thus each side member of the reel consists of a peripheral ring 1, and wire elements 2 welded inside of the peripheral ring and disposed wholly within the rings being suitably joined together in the hub or center of the reel and the two side members being connected in the hub to complete the construction.

100 105 6 indicates a cylindrical hub barrel preferably of sheet metal. The barrel 6 is provided at both its ends with a plurality of longitudinally projecting tongues 7 (see Fig. 4) spaced apart around the ends of the barrel. The tongues 7 enter the space between the spread apart ends 2' of the elements 2 and are turned over against the outer surface 110 of the hub plates 3 as indicated in Fig. 1, thereby locking the side members and the hub barrel together. Preferably the tongues

7 also fit in grooves or seats 8 formed in the periphery of the hub plates 3. When the parts are assembled the wire elements 2 are disposed in notches or seats 9 formed in the 5 ends of the hub barrel whereby they are firmly supported in place and also permit the end of the hub barrel to abut against the inner surface of the hub plate and make a closed joint.

10 It is not necessary that the tongues 7 engage the hub plate between the spread apart ends 2' as they might be disposed at other places around the periphery of the hub plates but by arranging them as shown they 15 are in such position that the sharp edges of the grooves 8 will not be apt to injure a person's finger should the reel be picked up by grasping the periphery of the hub plates when the reel is empty.

20 The hub plates 3 are provided with a central opening 10 for the supporting spindle and also with a key-way 11 so that the reel can be rotated by the spindle. 12 indicates a sheet metal sleeve for the spindle, said 25 sleeve passing longitudinally through the hub barrel 6 from one hub plate 3 to the other. The sleeve is provided with a longitudinal key-way 13 corresponding with the key-ways 11 in the plates 3. In forming the 30 sleeve 12 of sheet metal the edges of the blank are turned up to provide flanges 14. These flanges are cut away at each end of the sleeve to form a shoulder 15 at each end.

In assembling the two side members of 35 the reel to the hub barrel 6, the sleeve 12 is placed between the hub plates 3, the ends of the sleeve and the key-way 13 fit in the holes 10 and key-ways 11 of the plates 3. The hub plates 3 butt against the shoulders 15 40 and in this way when the hub plates 3 are locked to the hub barrel 6 by the tongues 7 the sleeve 12 is securely held in place without any further securing means and it cannot relatively move in any direction.

45 By so forming and securing the sleeve 12 the necessity of securing it in place by turning over the ends against the hub plates (as has been most commonly done in the past) is avoided. The serious objection to the old 50 practice is that the reel rotates against a fixed support and in a very short time the turned over ends of the sleeve are worn away and the sleeve becomes loose and drops out of the hub.

55 What we claim as our invention is:—

1. In a metal reel, a side member comprising a peripheral wire ring, a hub plate and wire elements bent in the plane of said peripheral ring joining the peripheral ring 60 and hub plate and each element having a bent portion engaging the inside of the peripheral ring and free ends intersecting a ridge on the hub plate and welded thereto.

65 2. In a metal reel, a side member comprising a peripheral wire ring, a hub plate pro-

vided with an annular ridge and wire elements joining the peripheral ring and hub plate, each element having free ends separated from each other and welded to said ridge and each element also being welded to each other and to the peripheral ring. 70

3. In a metal reel, a side member comprising a peripheral wire ring, a hub plate and wire elements joining the peripheral ring and hub plate and each having free ends 75 welded to the hub plate, the wire elements being welded to each other and to the peripheral ring and the free ends of adjoining elements being spread apart at the place of union with the side plates. 80

4. In a metal reel, two side members each comprising a peripheral wire ring, a hub plate and wire elements joining the hub plate and peripheral ring, and making side contact with one another and with the inside 85 of the ring, a hub barrel provided with seats for said wire elements and means securing the side members to the hub barrel.

5. In a metal reel, two side members each comprising a peripheral wire ring, a hub plate and bent wire elements joining the peripheral ring and hub plate, each said element having free ends welded to said hub plate and making contact with and welded by the outside of its bend to the inside of the peripheral ring, a sheet metal hub barrel provided with notches in which said wire elements are seated, said hub plates bearing against the ends of said barrel and means securing said side members to said hub barrel. 90 100

6. In a metal reel, two side members each comprising a peripheral wire ring, a hub plate and bent wire elements joining the peripheral ring and hub plate, and welded to the inside of said ring, each said element having free ends welded to said hub plate, a sheet metal hub barrel provided with notches in which said wire elements are seated, said hub plates bearing against the ends of said barrel and tongues locking said hub plates to said hub barrel. 105 110

7. In a metal reel, two side members each comprising a peripheral wire ring, a hub plate and wire elements joining the peripheral ring and the hub plate and each having free ends welded to the hub plate, the wire elements being welded to each other and to the peripheral ring and the free ends of adjoining elements being spread apart at the place of union with the side plates, a hub barrel against which the hub plates are seated and means located between the spread apart ends of the wire elements and securing the side members to the hub barrel. 115 120 125

8. In a metal reel, two side members each comprising a peripheral wire ring, a hub plate and wire elements joining the peripheral ring and the hub plate and each having free ends welded to the hub plate, the wire 130

- elements being welded to each other and to the peripheral ring and the free ends of adjoining elements being spread apart at the place of union with the side plates, a sheet 5 metal hub barrel intersecting said wire elements and locking tongues projecting through the space between said spread apart ends and turned over against the outer surface of the hub plates.
- 10 9. In a metal reel, the combination of a spindle sleeve, a pair of hub plates at opposite ends of said spindle sleeve having central openings concentric with, but of less size than said sleeve and seated against and embracing said sleeve between them, means for keying the spindle sleeve at its ends with the hub plates to prevent it from rotating with respect thereto and means surrounding the hub sleeve and tying the hub plates together independently of the sleeve thereby locking them against the sleeve in butted relation thereto to prevent longitudinal displacement of the sleeve in either direction.
- 15 10. In a metal reel, two side members each comprising a hub plate having a spindle opening, a hub barrel, means securing the side members to the hub barrel, a separate spindle sleeve in said hub barrel and projecting through the openings in the hub plates and a shoulder at each end of said spindle against which the hub plates seat, said spindle being secured in place by said first-named securing means.
- 20 11. In a metal reel, two side members each comprising a hub plate having a spindle opening, a hub barrel, means securing the side members to the hub barrel, a spindle sleeve in said hub barrel and projecting through the openings in the hub plates, and a longitudinal flange projecting laterally from said sleeve and terminating a distance from each end of the spindle sleeve, said hub plates being seated against the ends of said flange and said sleeve being secured in place by said hub securing means.
- 25 12. In a metal reel, the combination of two side members each comprising a hub plate having a spindle opening, a spindle sleeve extending from one to the other of said plates and against which inner faces of said plates are seated in butted relation to hold the sleeve against displacement in either direction, means for keying the sleeve and plates together to prevent rotation of the spindle with respect thereto, a hub barrel 50 surrounding said spindle sleeve and means at each end of said barrel for tying the plates thereto thereby tying them together and holding them seated in butted relation against the spindle sleeve.
- 30 13. A metal reel comprising two side members each consisting of a continuous peripheral wire ring and a plurality of wire elements connecting each wire ring with the center and engaging and welded to said ring in the plane thereof so that the reel at the point of attachment of said side members to the wire ring member will be free from lateral projections and hub plates at each end of the hub in which the said welded wire 55 elements of the said side members respectively terminate directly and to which they are welded.
- 35 14. A reel having two side members each consisting of a wire rim, a hub plate or disk and wire spoke elements welded to the inside of the wire rim and to the side of said hub plate or disk and a hub barrel or drum connecting said side members.
- 40 15. A reel having two side members each consisting of a wire rim, a hub plate or disk and wire spoke elements welded to the inside of the wire rim and cross-welded on a ridge on the side of said hub plate or disk and a hub barrel or drum connecting said side members.
- 45 16. A reel having two side members each consisting of a wire rim, a hub plate or disk and wire spoke elements welded to the inside of the wire rim and cross-welded on a ridge on the side of said hub plate or disk and a hub barrel or drum connecting said side members.

Signed at New York, in the county of New York and State of New York, this 9th day of July A. D. 1920.
